Primary Examiner — Kevin Rudzinski(74) *Attorney, Agent, or Firm* — Andrew Wilford(57) **CLAIM**

The ornamental design for a light fixture, as shown and described.

DESCRIPTION

FIG. 1 is a front perspective view of the invention;
FIG. 2 is a rear perspective view of the invention;
FIG. 3 is a front elevational view of the invention;
FIG. 4 is a left-side elevational view of the invention;
FIG. 5 is a right-side elevational view of the invention;
FIG. 6 is a bottom view of the invention; and,
FIG. 7 is a top view of the invention.

The instant invention is a generally parallelepipedal light fixture with a circular recessed lens on its front face and a disclaimed pivotal base fixed to its planar back face. An unillustrated light source inside the fixture projects a light beam out through the circular lens.
